UNITED STATES PATENT OFFICE.

EDWIN POLLARD, OF SILSDEN, ENGLAND, ASSIGNOR TO POLLARD & METCALFE, LIMITED, OF SAME PLACE.

DESIGN FOR A FIRE-KINDLER.

SPECIFICATION forming part of Design No. 34,550, dated May 21, 1901.

Application filed February 11, 1901. Serial No. 46,942. Term of patent 14 years.

To all whom it may concern:

Be it known that I, EDWIN POLLARD, a subject of the King of Great Britain, residing at Silsden, county of York, England, have invented and produced a new and original Design for Fire-Kindlers, of which the following is a specification, reference being had to the accompanying drawings, forming part thereof.

In the drawings, Figure 1 is a face view of my design. Fig. 2 is a view of the other face. Fig. 3 is a view of one edge, and Fig. 4 is a view of one side edge.

The leading feature of my design consists in a series of ribs *b* upon one face of the kindler, parallel with the sides thereof, with intervening channels *a* of the same width as the ribs *b*, while upon the opposite face are a series of channels *c* of the same width as the channels *a*, but diagonal to the sides, with intervening ribs *d* of greater width than the diagonal channels *c*, the said diagonal ribs toward the ends being shorter until the corners are reached, where they comprise triangular pieces *d'*. As seen in Fig. 3, showing one end of the kindler, the straight ribs *b* and channels *a* are of equal size, while the diagonal ribs *d* are of sufficient size to overlap a plurality of straight ribs and channels. In the side view, Fig. 4, the outside rib *b* appears with the adjacent ends of the diagonal ribs *d* and channels *c*.

Having thus described my invention, what I claim is—

The design for a fire-kindler as herein shown and described.

EDWIN POLLARD.
